UNITED STATES PATENT OFFICE.

CHARLES KIRCHHOF, OF NEW YORK, N. Y.

IMPROVED METHOD OF INTEGRATING INCONSTANT ELECTRIC CURRENTS.

Specification forming part of Letters Patent No. 31,545, dated February 26, 1861.

To all whom it may concern:

Be it known that I, CHARLES KIRCHHOF, of the city and county and State of New York, have invented an entirely new method of gathering, encompassing, retaining, and regenerating electricity produced in any way whatsoever or by any source or generator, and also of transforming the short and inconstant electric impulses or currents to a complete whole, which is as constant and identical as that produced in any other way, and which may be used at pleasure for the same purposes as any other electric current would or might be used.

Every experiment heretofore made for the purpose of dispensing with the galvanic batteries on account of the inconvenience, trouble, and expense attending them has turned out to be a failure, and the rapidly-increasing application of the electric current for practical purposes induced me to search for something practical, which will be attended with less trouble and expense. I have now invented an entirely new way, as stated above, and I do hereby declare that the following is a full and exact description thereof, reference being had to the accompanying drawings, and to the letters of reference marked thereon, in which—

Figure 1 is a perspective view of the device called "regenerator," and Fig. 2 is a perspective view of the device called "translator," and Fig. 3 is a transverse section of a current-changer of a magneto-electric machine.

To enable others skilled in the art to make and use my invention, I will proceed to describe its arrangements, construction, operation, &c.

I first refer to the well-known scientific researches of Ritter's charging-pile, Grove's gas-battery, Poggendorf's polarization apparatus, (producing short interrupted currents,) Mueller's improvement on Poggendorf's balance, (German *wippe*,) the researches on polarization by Schoenbein, Farada, Davis, and others, Wheatstone's hyperoxidated electrodes, (afterward combined with zinc or amalgam of potassium,) the devices of Poggendorf, Mendler, and others for integrating secondary currents, &c. No practical use has yet been made of these inventions, and I will now proceed to show that mine differs entirely, because it operates on the following principles: First, electric currents possessing a certain

amount of intensity, quantity, and resistance, or tensions of the two contrary electricities on re-establishing their equilibrium will never traverse an electrolytic liquid or similar compound without decomposing it partially, and the equivalents of the separated elements, being proportional to the activity of the current, will either surround the electrodes or escape in the form of gases or undergo any other chemical combination, and vice versa; second, two electrodes of different character or surrounded or covered by different electrolytes or substances excited by similar conducting liquids or solutions of similar character and possessing the property of dissolving at least one of them, or two electrodes of similar character, but immersed into different electrolytic liquids or different substances, which, in consequence of their affinity, have a tendency to produce, by entering into a combination, liquid chemical compounds, will produce an electric current proportional to the difference of their electro-chemical character; and therefore when a current has decomposed a certain amount of the electrolyte or electrolytes, and thereby disturbed the electro-chemical equilibrium and the separated elements (or their new combination) remaining in contact with the corresponding electrodes are disposed to restore the original equilibrium by a recombination, a reverse current will always be produced whenever the electrodes during the time of restoration are properly connected, unless chemical or physical local actions have taken place.

Any apparatus, arrangement, or device consisting of electrodes or conductors in combination or contact with or immersed into any electrolyte or electrolytes or chemical compound operating in the manner and on the principles as stated above may be called "regenerator," because if provided with the mechanical auxiliaries and arrangements which are indispensably necessary for the purpose of producing a favorable result it accepts, retains, collects, unites, and reserves or preserves the electricity generated or coming from any electric source whatsoever, and because it transforms any number of short impulses into a complete whole and reproduces a new and constant and continuous current corresponding to the charge and the arrange-

ments and liquids used, which current may be employed and used for all purposes like any other electric current, and also for counterbalancing and resisting other currents or tensions passing the same conductor in a contrary direction, &c., as I shall illustrate hereinafter.

The science of electrolysis has taught us a great deal of the generating and decomposing power of the electric current, the results of secondary action, *status nascens*, &c. I do not propose, however, to confine myself to any particular liquid, substance, or compound to be used for operating on my principles, or to any particular arrangement or construction. They may be chosen at pleasure. But, as regards to pecuniary economy and convenience, I should prefer as liquid the water and other cheap chemicals, because the "ozon" of the water (Schoenbein's definition) possesses the power, which cannot be surpassed by any other substance, of causing combinations of a very negative character, which may be easily disoxidized—as, for instance, the highest state of oxidation of manganese, potassium, sodium, barium, strontium, lead, iron, silver, &c., may be obtained by the electric current in the presence of water. Nitrogen ascends from NH_3 up to NO_5 , and strange are the results sometimes of the combinations of organic acids with inorganic elements. A reverse current of more or less activity is, however, in most cases the natural consequence.

An example may illustrate the practicability of my invention. Suppose a copper plate of a Daniels battery be immersed into diluted sulphuric acid or an acidulated solution of sulphate, nitrate amidide of copper, &c., and a copper or a zinc plate, both amalgamated with quicksilver into a solution of sulphate, nitrate, amidide, &c., of zinc. On connecting the electrodes with the corresponding ends of the conductors—as, for instance, the lightning-rod and the earth with the electrodes for the purpose of obtaining atmospheric electricity or the rubber and conductor of a friction-machine for the purpose of obtaining electricity by friction—the electricity of any source or generator may be stored up, which is, for instance, clearly explained hereinafter by the application of the magneto-electric machine.

A small and powerful regenerator is the following: A glass, (see Fig. 1) A, is closed by a cover of lead, B, to which electrodes of platina-foil C C are soldered, diverging from each other as they descend. Said electrodes are perforated, and I roughen them by hammering between emery-paper. They need not be platinaized.) A glass tube, E, inserted through a hole in the cover B, isolates the positive electrode D of platina, which is suspended in it and nearly extends to the bottom of the glass, where it spreads and branches around without touching, however, the other platina-foil. The glass is filled up with a solution consisting of about six parts, by weight, of nitrate of lead,

two to three parts of acetate of lead, and one part of nitrate of potash, dissolved in from eight to twelve times the quantity of water. The solution is now filtered and the following added: four parts of acetic acid, (liquid commercial at twenty-one per cent.,) one part of nitric acid, and scarcely one-sixteenth part of nitrate or acetate of iron, (or nitrate or acetate of zinc.) When too much of the iron is taken, the turning of the light color of the solution into a yellowish one will indicate it. On connecting the cover B with the positive pole P and the isolated electrode D with the negative end Z of any generator the foil will turn black peroxide of lead, and the positive electrode will be surrounded by crystallized lead. This is a very positive element, and the former peroxide the most negative known to exist, and also a good conductor.

By changing the proportions of the substances of the solution more or less peroxide or metal will be deposited, and the conducting-power, &c., may be increased or decreased in the same ratio. If pure ingredients are employed in the preparation of the solution it will last for a long time.

Metals of a more negative character than the above-named lead (except quicksilver) covering the positive electrodes are often very injurious. This is not the case, however, with the more positive elements. The combination of several cups or glasses is the same as in galvanic batteries.

Platina may be saved by substituting a positive electrode of lead (amalgamated with quicksilver) instead of platina.

Either of the following arrangements for controlling the current and regulating the resistance to be overcome by it will prove to be of great convenience.

The electrode is covered with a sliding non-conducting tube or funnel which may be raised or lowered for the purpose of exposing more or less surface of the electrode to the solution; or the electrode may slide up and down in the same; or the electrodes may be so arranged that they can be moved more or less apart from each other, when necessary; or the positive electrode may be made to collapse or press against a non-conductor, or any other similar arrangement. The electrode may also enter through the bottom. Said bottom may be concave or conical. In this way the deposits will be collected around the electrode, thus giving the current a chance to easily affect and dissolve them again. Amalgams may also be used for positive electrodes.

A more perfect apparatus is the double regenerator. Each glass of the same is provided with two pairs of electrodes, each pair acting independent of the other. One pair discharges while the other gets charged. In this manner the quantity of the elements of the solution remains the same. In some cases one positive electrode may answer at the same time for the two negative ones. All regener-

ators may be used for discharging quantitative currents while being charged.

For the purpose of conducting the currents at the proper time to the proper place and in the proper direction, and also for opening and closing the circuits when required, and in order to facilitate the regular charging and discharging, mechanical contrivances are required, which I will call "translator."

I will refer at first to the contrivances designed by Poggendorf and Mueller for the purpose of aiding them in their scientific researches, which I have improved and made to answer for practical purposes. As to Poggendorf's, I cover the board with a strap of wood containing corresponding holes. Between the board and strap I put a layer of thin india-rubber, or a similar substance, with very fine holes in it, which permit the pins or hooks to be dipped into the quicksilver. In this way the waste and evaporation of the latter is prevented. Furthermore, a key for opening and closing the circuits may be arranged in such a manner that it will not close or open the circuits until all the pins shall have been dipped into the quicksilver. In this way the oxidation of the latter by means of the electric spark is avoided. Said key may also be used to operate at the required time the balance with greater precision, and may be withdrawn by a spring or its equivalent whenever released by the finger, &c., or, vice versa, the balance may operate the key. A similar arrangement must also be added to Mueller's, with this difference, however, that either the cylinder has to be turned by it step by step, or, vice versa, the cylinder may move it, or a slide may be substituted for the cylinder operating the springs in a similar manner, &c. For double charging, a double combination of the translator is required.

Convenient contrivances operated by any desired motive power, as electro-magnetism, &c., or the combination of the translator with other arrangements, as telegraph apparatuses, magneto-electric machines, &c., will often be necessary for the purpose of causing the required changes of the course or presence or absence of the currents and for operating correspondently—as, for instance, causing either temporary or integral currents, which act for a certain and at a certain time and with a certain amount of power, for the purpose of operating electric clocks, signal apparatuses, starting, moving, or stopping mechanism, or to and fro, or strong and feeble currents, &c.—but in such cases the liquid may also help. Taking water to be one of the worst electrolytes and conductors, an addition of sulphuric, hydro-chloric, nitric acid, or salts of the series of alkalies and positive metals will increase the activity in proportion. Short impulses or to and fro currents permit also the conductor to remain closed afterward, and the reaction of the induction currents or electric tensions will be prevented, because they will be counter-

balanced by the polarization on the passage of the induction-currents through the regenerator.

The next illustrated arrangement of the translator will show the possibility of charging the regenerator or polarization apparatus at any and the same time while it is discharging. Suppose some cups, Fig. 2, B' B'' B''' B''', to be connected with each other, forming a circuit of great intensity. To each connection F' F'' F''' F'''' a wire, G' G'' G''' G''''', is attached, the end of which touches a wooden cylinder, L, surrounded spirally by two wires, H K, which run parallel with each other, but are so far apart that on turning the cylinder only one spring touches one spiral at a time. Each spiral H K is connected with a journal, M N, (isolated,) of the cylinder L, and each journal by a spring, O Q, with the corresponding pole P' Z' of the generator, Fig. 3, and on turning the cylinder L cup by cup will be charged by the translator. A circular arrangement around a vertical revolving shaft, with two isolated projections touching against the springs, or a movable slide slowly progressing or raising, will produce the same effects.

It is obvious that by the application of all such arrangements, as explained above, the polarization apparatus will likewise answer in many cases for practical purposes, especially by the application of temporary currents. Finally, it will be necessary for me to dwell a little longer yet on the manner of gathering, retaining, and transforming the short or momentary impulses of induction-currents, especially the currents of the magneto-electric machine.

All the innumerable arrangements which have been devised for the purpose of combining separate impulses in such a manner as to give them the semblance of a constant and continuous current have so far proved unsuccessful, and none of the learned and scientific men of the civilized world have yet been able to demonstrate the possibility that a perfect and continuous current, like a galvanic current, which does not vibrate in the least, can be obtained by any means. Mine, therefore, is the only method by means of which the impulses are collected by the regenerator and then united, transformed into a complete whole, and reproduced anew, as required. For this purpose, however, and in order to obtain as much electricity as possible, the following auxiliary arrangements must be observed: First, the discharge of the currents through all the helices into the general conductor must take place at the same time; second, it is necessary that the resistance of all the helices which are connected together be a little in excess over the resistance of the regenerator; third, the current-changer must be constructed in such a manner as to furnish to the electricity collected in the regenerator no way of escape through the closed circuit of the helices during the time in which they produce too little or no electricity. For instance, the ends of the helices are con-

nected with two springs, (see Fig. 3,) V U, which are diametrically attached (isolated) to the main shaft T, and their other ends touch against a concentric stationary metallic ring, consisting of two isolated segments, R S; (of which one is larger and the other smaller than a semicircle,) and to which the poles P' Z' of the regenerator are fastened. The magnets being directly opposite the electro-magnets, both springs V U have to touch the large segment R, thus leaving the circuit closed and the communication with the regenerator is stopped, because one pole, P', is fastened to the small segment S.

The combination of the magneto-electric machine, translator, and regenerator is at the present time the only method by which a continuous current can be obtained, because it works on the principle of a pump with air-chamber or a pair of bellows with reservoir. If the machine is constructed in the manner indicated by me and operated by a weight the current expenses for having on hand a constant electric current at all times are not worth speaking of.

It will be easily understood that the translator may also be operated by the motion of the machine, as mentioned before.

Having now clearly specified and illustrated my invention, I shall proceed to state what I disclaim and what I want to have secured by Letters Patent. I do not claim anything referred to as being well-known; but

I do claim—

1. The device called "regenerator," arranged in such manner as to operate on the principles and in the manner as stated.

2. The arrangements, construction, and devices called "translator," and the improvements made for opening and closing the circuits with precision and for conducting and interrupting the charging and discharged currents as desired, the said translator and improvements to be applied and operated as described.

3. The combination of said arrangements and devices mentioned in the preceding claim with the regenerator as well as with the polarization apparatus.

CHARLES KIRCHHOF.
